UNITED STATES PATENT OFFICE.

LEONARD CONRAD, OF PASADENA, CALIFORNIA.

ADJUSTABLE CRADLE.

1,268,327.

Specification of Letters Patent. Patented June 4, 1918.

Application filed October 3, 1917. Serial No. 194,534.

To all whom it may concern:

Be it known that I, LEONARD CONRAD, a citizen of the United States, residing at Pasadena, in the county of Los Angeles, 5 State of California, have invented certain new and useful Improvements in Adjustable Cradles; and I do hereby declare the following to be a full, clear, and exact description of the invention, such as will enable others 10 skilled in the art to which it appertains to make and use the same.

This invention is an improvement in surgical apparatus and has particular reference to an adjustable cradle.

15 An object of the invention is the provision of a cradle for supporting the bed clothing and principally employed in abdominal cases and which may also be utilized for protecting the arms and legs of a patient whereby 20 to prevent the clothing from coming in contact with the patient and, in carrying out this object, use is made of a pair of frames adjustable longitudinally relative to each other, each frame consisting of sections 25 which are laterally adjustable relative to each other so that the entire device may be properly mounted over different parts of the body.

Another object is to so construct the frame 30 and sections thereof that the same may be readily and quickly disassembled whereby the parts may be cleaned and sterilized.

A further object is the provision of a device of this character which is simple in construction, easy to manufacture and effective in carrying out the purpose for which it is 35 designed.

The inventive idea involved is capable of receiving a variety of mechanical expressions, one of which, for the purpose of illustrating the invention, is shown in the accompanying drawing, wherein:—

40 Figure 1 is a side elevation of the cradle constructed in accordance with the invention.

Fig. 2 is a plan view showing an adjustment of one of the frames in dotted lines.

Fig. 3 is a central longitudinal section.

Fig. 4 is a perspective view of one of the 50 complementary sections of the main frame.

Fig. 5 is a similar view of one of the complementary sections of the auxiliary frame.

Fig. 6 is a section on the line 6—6 of Fig. 2.

The accompanying drawing illustrates 55 what is now believed to be a preferred form of the invention which is made of aluminum or other like material and which comprises a main frame generally indicated by the numeral 10 and an auxiliary frame 11 adjustable longitudinally of said main frame.

The main frame 10 consists of a pair of complementary sections generally indicated by the numeral 12, each section comprising a plurality of longitudinal ribs 13 arranged 60 in spaced parallel relation and connected by the relatively wide transverse end and intermediate ribs 14 and 15 respectively arranged on the inner sides of said longitudinal ribs and secured thereto in any preferred 65 manner. The inner adjacent ends of the ribs 14 and 15 are curved as indicated at 16 and when the frame 10 is assembled these inner ends are adapted to overlap. In order to secure said ends in overlapping relation 70 there is preferably provided a central longitudinally extending, relatively stationary bar 17 having a plurality of transverse guide members 18 secured thereto by soldering or otherwise, said guide members corresponding 75 in number to the number of transverse ribs 14 and 15. These guide members are provided with oppositely disposed flanges 80 19 and the intermediate member receives therebetween the overlapping ends of the intermediate transverse ribs 15 of the two sections of the main frame. The adjacent overlapping ends of the end transverse ribs are provided with longitudinal slots 20 which register with each other and receive therein 85 the fastening bolts or screws 21 one of which extends through the central bar 17 and said screws have mounted thereon the wing nuts 22 which, when tightened, will maintain the sections of the main frame in adjusted positions, it being understood that said sections are adjustable laterally relative to each 90 other and to the central bar 17.

The auxiliary frame 11 preferably comprises a central bar 23, carrying a guide 100 member 24 for receiving the inner end of the bar 17 which is slidably mounted in said guide member 24, and said bar 23 has a longitudinal slot 25 therein for receiving the screw 25' which is carried by the inner 105 end of the bar 23, thus permitting of a relative longitudinal adjustment between the bars 23 and 17. The auxiliary frame further

- comprises a pair of sections, each of which consists of a transverse rib 26 having the longitudinal ribs 27 extending therefrom and engageable in guide members 28 carried by the inner ends of the longitudinal ribs 13 of the main frame 10 thus maintaining the frames in operative relation and permitting of a relative longitudinal adjustment. The outer end of the bar 23 is provided with a transverse guide member 29, similar in construction to the guide members 18 and receiving ribs 26 of the auxiliary frame, which ends are provided with elongated registering slots 30 which receive the screw fastener 31 having the wing nut 32 mounted thereon for the purpose of screwing the sections of the auxiliary frame in adjusted position.
- The inner transverse ribs of the sections of the main frame 10 are extended as indicated at 33 and have pivoted thereto the ribs 34 of the main frame. Each rib 34 has pivoted to its free end an arm 35 which extends laterally therefrom and longitudinally of the adjacent rib of the main frame, and is provided with a longitudinal slot 36 for receiving a screw fastener 37 carried by the said adjacent transverse rib and having a wing nut 38 thereon for engaging said slotted arm to maintain the rib 34 in adjusted positions.

It will be apparent from the foregoing description that the sections of the main and auxiliary frames may be adjusted laterally, relative to each other and that the frames are adjustable longitudinally of each other by unscrewing the several wing nuts and then tightening the same to secure all of the parts in their adjusted positions. It will also be seen that by removing the several wing nuts and screws the parts may be disassembled for the purpose of cleaning and sterilizing the same.

What is claimed is:—

1. A surgical cradle of the character described, comprising a main frame and auxiliary frames adjustable longitudinally relative to each other, each frame including laterally adjustable sections, means for securing the frames in their adjusted positions, longitudinal ribs pivoted at one end to said main frames, and means associated

with the free ends of said ribs for securing the same in adjusted positions.

2. A surgical cradle of the class described comprising a main frame including a central bar, transverse ribs adjustable laterally relative thereto, longitudinal ribs secured to said transverse ribs, and means associated with said central bar for securing said transverse ribs in adjusted positions. 60

3. A surgical cradle of the class described including a central bar, guide members mounted transversely thereof, a frame associated with said bar including a pair of sections adjustable laterally relative to each other, each section including transverse ribs having their adjacent ends overlapped and slidably mounted in said guide members, and means for securing said sections in adjusted positions. 70

4. A surgical cradle of the class described comprising a main frame including a central bar, transverse ribs adjustable laterally relative thereto, longitudinal ribs secured to said transverse ribs, means associated with said central bar for securing said transverse ribs in adjusted position, guide members carried by said longitudinal ribs, and an auxiliary frame including longitudinal ribs slidably mounted in the last named guide members. 75

5. A surgical cradle of the class described comprising a main frame including a central bar, transverse ribs adjustable laterally relative thereto, longitudinal ribs secured to said transverse ribs, means associated with said central bar for securing said transverse ribs in adjusted positions, guide members carried by said longitudinal ribs, an auxiliary frame including longitudinal ribs slidably mounted in the last named guide members, said auxiliary frame including sections adjustable laterally relative to each other, and means for securing said sections in adjusted positions. 90 95

In testimony whereof, I affix my signature in the presence of two witnesses:

LEONARD CONRAD.
